UNITED STATES PATENT OFFICE.

JAMES IHRIE LEARY, OF CHICAGO, ILLINOIS.

PRINTING APPARATUS FOR ROLL-PAPER.

1,164,730.

Specification of Letters Patent. Patented Dec. 21, 1915.

Application filed March 1, 1915. Serial No. 11,341.

To all whom it may concern:

Be it known that I, JAMES IHRIE LEARY, a citizen of the United States, residing at Chicago, in the county of Cook, State of Illinois, have invented a new and useful Improvement in Printing Apparatus for Roll-Paper, of which the following is a specification.

My invention relates to improvement in printing apparatus for printing roll paper, such apparatus being provided with means for automatically inking the ink rolls and where, by the use of such inking attachment several colors may be printed; also I provide means for firmly clamping the apparatus to the stand holding the roll paper thus preventing its slipping off or getting out of adjustment in relation to its position in respect to the paper to be printed.

I attain these objects by the mechanism illustrated in the accompanying drawing in which—

Figure 1 represents the side view of the machine showing a section also of the paper roll holder wherein an adjustable position of the cover holding the ink fountains is shown by dotted line. Fig. 2 represents a plan view showing a partial interior of the machine. Fig. 3 represents a vertical section through the ink fountain (9). Fig. 4 represents a plan view showing a partial interior of the ink fountain.

Similar letters refer to similar parts throughout the several views.

(9), (9), (9), represent ink fountains provided with wicks (17) and stoppers (19), said wicks being held in ferrule tubes (24), which tubes project inwardly into the ink fountains and terminate near their upper portion; the other end of such tubes passing through the bottom of the fountain in such a manner as to hold the wick in operative relation with the ink roller (5).

(10) is a cover hinged about an axis (14) and fitted with the clamp screw (7) which clamp screw is in operative relation with a cross member (25) of the machine. The ink fountains (9) are attached to the cover (10) in such a manner as to occupy different positions with respect to the ink roller (5) and the tubes (24) project through the cover (10).

(12) is a handle attached to the ink roller (5) in such a manner that the ink roller may be rotated independently of the other mechanism of the machinery for the purpose of

distributing the ink on the roller without disturbing the other mechanism. This handle is screwed into the roller as shown by dotted line and may be removed for the purpose of removing the roller. The axis of the handle (12') is provided with a spring (11') which fits over the same in the form of a loose collar. The other end of such spring being firmly held to the frame of the machine thus providing a tension.

(3) is a roller provided with impression type, such as rubber.

(4) is an intermediate ink roller provided with a removable screw axis (13), which axis and also the axis of the roller (5) operate in slotted bearing allowing a radial adjustment. The printing roller (3) is mounted on a removable screw axis (3').

(26) is a section of a cross bar of the paper holder.

(16) is a clamp screw which works in a bearing through the clamp frame (6).

(15) is a loose fitting member provided with a projecting point.

(14) is a similar member but firmly attached to the frame of the machine being also provided with a projecting point, such projecting point, may if desired, be in plurality and they serve the purpose of holding the machine firmly by embedding themselves into the wooden structure (26).

(8) is an extension rod of a spiral spring fitting around the axis (14) loosely which serves to keep the roller (3) pressed toward the paper roll.

(1') is the axis of the paper roll (1).

(20) is the paper cutter.

The operation of the machine is as follows: The desired type is formed on the roller (3) which is kept pressed against the roll of paper (1) by the spring extension rod (8) which rests on the opposite side of the axis (3). Ink is then applied to the rollers (4) and (5) and the handle (12) is turned until such ink is distributed. Ink is then poured into the fountains (9) and as the ink is exhausted from the rollers (4) and (5) it is automatically replenished from the fountains (9) by passing through the wicks (17). If it is desired to print in three colors the different colored inks are placed in the three respective fountains and the rollers (4) and (5) are inked at their respective portions with the ink corresponding to the ink in the fountain, opposite such portion and in this way the three colors blend into

each other producing a desirable effect and at the same time are replenished as they are exhausted by the supply of each respective fountain. To regulate the tension or pressure of the wick (17) against the roller (5) the adjusting screw (7) may be used to raise or lower the frame (10) bringing the wick nearer to or farther from the roller (5) and in such position as to procure the right pressure to allow the free movement of the roller (5) where it may be clamped by tightening the adjusting screw (7). The printing roller (3) and the rollers (4) and (5) are revolved by friction against the paper roller (1) as the paper is pulled off.

(19) is a stopper fitting for admitting ink.

Having thus described my invention, I claim:

The combination of a machine for printing roll paper comprising a hinge cover over

the inking rollers to which cover is attached one or more ink fountains provided with wicks extending downwardly through a tube through such cover and contacting with the ink roller and means for raising and lowering the position of such fountains and wicks by a clamp adjusting screw attached to the opposite portion of such cover so as to engage the frame of the machine for the purpose of holding such cover and wick in proper adjustment with the ink roller of such machine and the removable handle attached to such ink roller for the purpose of rotating such roller independent of the other mechanism of the machine.

JAMES IHRIE LEARY.
